UNITED STATES PATENT OFFICE

EDWARD KINSELLA, OF SPONDON, NEAR DERBY, ENGLAND, ASSIGNOR TO CELANESE CORPORATION OF AMERICA, A CORPORATION OF DELAWARE

PUMPING APPARATUS FOR ARTIFICIAL-SILK SPINNING SOLUTIONS

Application filed February 25, 1928, Serial No. 257,015, and in Great Britain December 21, 1927.

This invention relates to new or improved pumping apparatus for delivering artificial silk spinning solutions or other applications, especially such applications as require liquids or solutions to be delivered under pressure with a high degree of regularity.

Pumping apparatus according to the invention comprises one or more pumping units each comprising a pump, a static measuring device, and a pressure balance valve so arranged and combined that the delivery side of the pump communicates with the inlet side of the static measuring device through one side of the pressure balance valve the motor member of which pressure balance valve is subjected on this side to the pressure of the inlet side of the static measuring device and on the other side to the pressure common to the delivery side of the static measuring device and the spinning jet or jets or other point of use, which motor member carries or is arranged to operate a valve member of the pressure balance valve to control the supply of spinning solution or other fluid to the pump 25 from the source of supply.

By the term static measuring device I mean an orifice, capillary tube, constriction or equivalent device adapted to pass a given or measured volume of fluid by virtue of a given pressure difference existing between the inlet side and the outlet side of the said device.

The pump of the pumping unit or of each pumping unit may be of any suitable type as for instance of the gear wheel type or of the piston type.

The pressure balance valve of the pumping unit or of each pumping unit may for instance be of the piston type, the piston of the said balance valve being subjected on its respective opposite sides to the before mentioned pressures and carrying or arranged to operate a valve member of the pressure balance valve (for instance a needle valve member, or a double conical valve member, or a slide valve of the piston or other type) to control the supply of spinning solution or other fluid to the pump from the source of supply.

Or, for instance, the pressure balance valve 50 of the pumping unit or of each pumping unit

may be of the diaphragm type, the diaphragm of said balance valve being subjected on its respective opposite sides to the before mentioned pressures and carrying or arranged to operate a valve member of the pressure balance valve (for instance a needle valve member, or a double conical valve member, or a slide valve of the piston or other type) to control the supply of spinning solution or other fluid to the pump from the source of supply. 55

Any suitable means may be employed to provide a definite and substantially unvarying pressure difference across the static measuring device (i. e. between the two sides 65 thereof),—irrespective of the pressure required to overcome the resistance of the point of use of the pumping unit,—and for compensating for the drop in pressure occurring 70 in the spinning solution or other fluid in its passage through the static measuring device and thus by this compensation enabling a balance of pressures to be established against the respective sides of the motor member of the pressure balance valve. For instance the piston, 75 diaphragm or other motor member of the pressure balance valve may be arranged to work against the pressure of a spring, or for instance the piston of the pressure balance valve may be arranged to work against the force of gravity. 80

The pressure balance valve of the pumping unit or of each pumping unit is preferably so constructed and arranged to operate that its valve member entirely cuts off the supply 85 of fluid to the pump of the pumping unit when an excess out-of-balance pressure develops on the delivery side of the static measuring device, i. e. when, owing for instance to bad choking of the spinning jet or jets 90 or other point of use, the pressure on the delivery side of the static measuring device rises above the pressure capacity of the pump. By these means delivery from the pumping unit concerned is stopped (and prevented from 95 giving incorrect delivery) until the cause of the out-of-balance condition is removed.

If desired the pressure balance valve of the pumping unit or of each pumping unit may be so constructed and arranged to operate 100

that its valve member entirely cuts off the supply of fluid to the pump of the pumping unit when an excess out-of-balance pressure develops on the inlet side of the static measuring device.

In performing the invention for the delivery of cellulose acetate solutions or other solutions or fluids the viscosity of which varies with the temperature, and especially when delivering such solutions in the spinning of artificial silk, I preferably provide in association with the static measuring device a compensating device adapted to act under variation of temperature to control the orifice or other form of static measuring device so that the flow through the static measuring device, and hence the delivery from the pumping unit, remains uniform under variations of temperature. For instance, I may provide a small valve operated by a bi-metal strip or by a spirit capsule or any other thermally operated device to control the aperture of the orifice or other form of static measuring device employed.

When using the apparatus of the invention for the spinning of artificial silk I preferably employ a number of the pumping units fed from the common source of supply, one pumping unit being preferably employed for each artificial silk spinning jet or nozzle.

The accompanying drawings serve to illustrate some forms of the invention, it being understood that they are given only by way of illustration and are in no way limitative.

Figure 1 is a view of one form of pumping unit in accordance with the invention, the pressure balance valve (shown in vertical section) in this form being of the piston type, the piston of which operates a slide valve member of the piston type to control the supply of spinning solution to the pump from the source of supply. The form illustrated in this figure also comprises a valve operated by a bi-metal strip to control the aperture of the static measuring device, with a view to ensuring uniformity of delivery from the unit under variation of temperature.

Figure 2 is an elevation of the piston and slide valve member shown in Figure 1.

Figure 3 is a vertical detail sectional view showing the static measuring device and aperture controlling valve of Figure 1 on an enlarged scale.

Figure 4 is a view of one form of pumping unit in accordance with the invention, the pressure balance valve (shown in vertical section) in this form being of the diaphragm type, the diaphragm of which is arranged to operate a double conical valve member to control the supply of spinning solution or other fluid to the pump from the source of supply. The form illustrated in this figure also comprises a valve operated by a spirit capsule to control the aperture of the static measuring device, with a view to ensuring

uniformity of delivery under variation of temperature.

Figure 5 is a diagrammatic view illustrating apparatus according to the invention applied to a metier or cabinet for the spinning of artificial silk by the dry or evaporative method of formation, the figure showing diagrammatically a number of pumping units similar to that shown in Figures 1, 2 and 3, fed with spinning solution from a common source of supply; two pumping units are shown in the section or portion of the spinning apparatus shown in this figure, it being understood that the apparatus may comprise any desired number of pumping units similarly connected to and fed by the source of supply. The source of supply is not shown in this figure but may be any means (for instance a pump of the gear wheel or piston type) suitable for supplying the spinning solution, under relatively low pressure, to the pumping units.

Referring to Figure 1, 1 is the inlet from the source of supply. 2 is the pump; this pump in the case illustrated being of the gear wheel type. 3 is the pressure balance valve, 4 is the static measuring device, this in the form illustrated being of the orifice type. The casing 5 of the pressure balance valve is formed with two bores of different diameters, and has a piston 6 working in the lower and larger bore, and a hollow slide valve member 7 working in the upper and smaller bore. The casing may, if desired, be bored to a uniform diameter instead of to the two different diameters, but I have found the form shown to be advantageous when dealing with artificial silk spinning solutions or other fluids requiring great sensitivity of control. The piston 6 divides the interior of the casing 5 into an upper chamber 8 and a lower chamber 9, and the valve member 7 is provided with the holes 10 communicating with its interior for enabling the piston 6 and slide valve member to move under variation of pressure. The upper chamber 8 communicates via the port 11 with the port 12, and hence with the static measuring device 4, and with the outlet pipe 13 leading to the spinning jet or jets or other point of use. The lower chamber 9 communicates via the port 14 with the delivery side of the pump 2 and via the port 15 with the inlet side of the static measuring device 4.

The inlet 1 from the source of supply communicates with the pump 2 via the annular groove 16 in the casing 5, the inclined annular groove 17 around the slide valve member 7, the annular groove 18 in the casing 5, and the inlet port 19 of the pump 2. By the positioning of the inclined groove 17 relatively to the annular grooves 16 and 18 the slide valve member 7 controls the supply of spinning solution or other fluid fed to the pump 2 from the source of supply.

The static measuring device 4, shown on a larger scale in Figure 3, comprises a disc 20 which is formed with an orifice 21, this orifice constituting the true static measuring device. It will be understood that the means shown in Figure 1 for mounting the disc 20 are purely diagrammatic and that any suitable means of mounting may be employed, for instance the disc may be held between an annular shoulder in the port 12 and a threaded ring, or it may be brazed or soldered to an annular shoulder in the port 12.

The piston 6 works against the pressure of the spring 22, the pressure of this spring serving to establish the desired pressure difference across the static measuring device 4, and, by serving to compensate for the drop in pressure occurring in the spinning solution or other fluid in its passage through the static measuring device, enabling a balance of pressures to be established against the respective sides of the piston 6.

In normal operation the spinning solution or other fluid passes from the source of supply (not shown), for instance from a gear wheel pump, under any suitable and relatively low pressure to the inlet pipe 1. From the inlet pipe 1 the fluid passes via the annular groove 16 in the casing 5, the inclined groove 17 around the slide valve member 7, the annular groove 18 in the casing 5, the port 19 and through the pump 2. From thence the spinning solution or other fluid passes via the port 14, lower chamber 9, port 15 and through the static measuring device 4; thence via the port 12 to the upper chamber 8 and the outlet pipe 13 and passes from the outlet pipe 13 to the spinning jet or jets or other point of use.

With the arrangement shown, substantially only the correct amount of spinning solution or other fluid is permitted to be fed to the static measuring device, as any pressure in the lower chamber 9 in excess of the pressure in the upper chamber 8 (i. e. the pressure of the fluid in the upper chamber 8 plus the pressure of the spring 22) causes the piston 6 to move upwards and reduce the amount of fluid admitted to the pump 2 by restricting the aperture between the inclined groove 17 around the slide valve member 7 and the annular grooves 16 and 18 in the casing 5, the piston 6 and slide valve member 7 moving upwards until a balance of pressures is created on the respective sides of the piston 6; conversely, if the resistance in the spinning jet or other point of use rises (due for instance to partial choking of the spinning jet or other point of use) it means that the pressure in the upper chamber 8 must also rise to overcome this resistance, this causes the piston 6 to move down and increase the aperture between the inclined groove 17 and the annular grooves 16 and 18 (and thus increasing the amount of fluid fed to the pump 2), the pis-

ton 6 and slide valve member moving down until a balance of pressures is created on the respective sides of the piston 6, the pressures of the fluid in the upper and lower chambers being then higher than before. So long as the total pressures against the respective sides of the piston 6 are equal, the pressure on the delivery side of the static measuring device is always substantially that required to feed the measured quantity of fluid to the spinning jet or jets or other point of use. In passing it should be noted that the supply of fluid from the inlet 1 to the pump 2 is at a maximum when the upper and lower extremities of the inclined groove 17 are in register respectively with the annular groove 16 and the annular groove 18.

If an abnormal or excess out-of-balance pressure develops in the upper chamber 8, i. e. on the delivery side of the static measuring device, (due for instance to the spinning jet or jets or other point of use becoming badly choked) such that the resistance in the delivery from the pumping unit rises above the pressure capacity of the pump, the piston 6 descends sufficiently to move the inclined groove 17 out of register with the annular groove 16, thus cutting off communication entirely between the inlet pipe 1 (and hence the source of supply) and the inlet port 19 of the pump 2, the pumping unit ceasing to deliver the spinning solution or other fluid to the spinning jet or jets or other point of use until the cause of the out-of-balance condition is removed. Conversely, if any abnormal or excess out-of-balance pressure develops in the lower chamber 9, i. e. on the feed side of the static measuring device, the piston 6 rises sufficiently to move the inclined groove 17 out of register with the annular groove 18, thus cutting off communication entirely between the inlet pipe 1 (and hence with the source of supply) and the inlet port 19 of the pump 2, the pumping unit ceasing to deliver the spinning solution or other fluid to the spinning jet or jets or other point of use until the cause of the out-of-balance condition is removed.

In the form shown in this figure means are provided to ensure constant delivery from the pumping unit under variation of temperature when employing liquids (especially solutions of cellulose acetate or other cellulose derivatives in volatile solvents) the viscosity of which decreases with an increase of temperature. As such means a small valve 23 operated by the bi-metal strip 24 (for instance a bi-metal strip of brass and iron) is provided to control the orifice 21 of the static measuring device, the valve 23 being fixed to one end of the bi-metal strip 24 the other end of which is fixed to the casing 5. Any increase in temperature causes the bi-metal strip 24 to raise the valve 23 to

restrict the aperture between the valve 23 and the orifice 21, and conversely any decrease in temperature causes the bi-metal strip 24 to lower the valve 23 and enlarge the aperture between the valve 23 and the orifice 21.

For starting up the unit when the communication between the inlet pipe 1 and the pump 2 is cut off by the valve member 7 (i. e. when the inclined groove 17 is out of register with either of the annular grooves 16 or 18), for instance when starting up the pumping unit initially, or after removal of the cause of either of the before mentioned excess out-of-balance conditions, the screw valve member 25 is temporarily opened to allow fluid to pass from the supply pipe 1 via the annular groove 16 and the port 26 and port 19 to the pump 2. Fluid so passing to the pump 2 passes from the pump via the port 14, the lower chamber 9, the static measuring device 4 and port 12 to the upper chamber 8, and thus moves the piston 6 to move the valve member 7 to open communication between the annular grooves 16 and 18 and the inclined groove 17 and put the pumping unit in operation.

The apparatus shown in Figure 1 is provided with a screw plug 27 provided with a channel 28. On first starting the pumping unit or on restarting the pumping unit after it has become emptied of fluid, the plug 27 may be unscrewed sufficiently for the channel 28 to communicate with the atmosphere, thus enabling air in the unit to be displaced by the spinning solution or other fluid, and when the unit is full of fluid the plug 27 is screwed down to close the channel 28.

If desired the spring 22 may be omitted and a suitably heavy piston 6 be employed, in which case the weight of the piston 6 will serve to establish the desired pressure difference across the static measuring device, and, by serving to compensate for the drop in pressure occurring in the fluid in its passage through the static measuring device, enable a balance of pressures to be established on the respective sides of said piston.

Referring to Figure 4, this figure shows a similar form of pumping unit to that shown in Figures 1, 2 and 3 but the pumping unit shown in Figure 4 comprises a pressure balance valve of the diaphragm type, the diaphragm of which operates a double conical valve member to control the supply of fluid to the pump of the unit; and, in this figure the valve for controlling the static measuring device is operated by a spirit capsule instead of by a bi-metal strip.

Referring to Fig. 4, 1 is the inlet pipe leading from the source of supply. 2 is the pump, this pump in the case illustrated being of the gear wheel type. 3 is the pressure balance valve. 4 is the static measuring device, this in the form illustrated being of the orifice type. The casing 5 of the pressure balance

valve 3 is provided with a bore in which the diaphragm 6 is fitted, this diaphragm being held between the annular shoulder 7 and the threaded ring 9. The diaphragm divides the bore of the casing 5 into an upper chamber 10 and a lower chamber 11, and carries a member 12 which extends upwards from the diaphragm through a bore 13 in the casing 5 and terminates in the double conical valve member 14. The bore 13 is provided with suitable annular grooves or the like 15, to prevent fluid leaking from the chamber 10 through the bore 13.

The lower chamber 11 communicates via the port 16 with the delivery side of the pump 2, and also communicates with the static measuring device 4. The upper chamber 10 communicates via the port 17 with the outlet pipe 18A leading to the spinning jet or jets or other point of use, and via the port 17 and port 18 with the static measuring device 4, this device being constituted by a circular orifice 19 between the port 18 and the lower chamber 11. The inlet pipe 1 communicates via the port 20, the throat 21 and the inlet port 22 with the inlet side of the pump 2, and by the position of double conical valve member 14 relatively to the throat 21 the supply of fluid to the pump 2 from the supply pipe 1 is controlled.

The diaphragm 6 works against the pressure of the spring 23, the pressure of this spring serving to establish the desired pressure difference across the static measuring device 4, and, by serving to compensate for the drop in pressure occurring in the spinning solution or other fluid in its passage through the static measuring device, enabling a balance of pressures to be established against the respective sides of the diaphragm 6.

In normal operation the spinning solution or other fluid passes from the source of supply (not shown), for instance a gear wheel pump, under any suitable and relatively low pressure to the inlet pipe 1. From the inlet pipe 1 the fluid passes via the port 20, throat 21 and port 22, to the pump 2. From thence it passes via the port 16, lower chamber 11, through the static measuring device 4 to the port 18. From the port 18 the fluid passes to the outlet pipe 18A leading to the spinning jet or jets or other point of use and via the port 17 to the upper chamber 10.

With the arrangement shown, substantially only the correct amount of spinning solution or other fluid is permitted to be fed to the static measuring device, as any pressure in the lower chamber 11 in excess of the pressure in the upper chamber 10 (i. e. the pressure in the upper chamber 10 plus the pressure of the spring 23) causes the diaphragm 6 to move upwards and reduce the amount of fluid admitted to the pump 2 by restricting the aperture between the lower cone of the 130

double conical valve member 14 and the throat 21, the diaphragm 6 and double conical valve member 14 moving upwards until a balance of pressures is created on the respective sides of the diaphragm 6; conversely, if the resistance in the spinning jet or jets or other point of use rises (due for instance to partial choking of the spinning jet or jets or other point of use) it means the pressure 10 in the upper chamber 10 must also rise to overcome this resistance, this causes the diaphragm 6 to move down and increase the aperture between the lower cone of the double conical valve member 14 and the throat 21 15 (and thus increase the amount of fluid fed to the pump 2) sufficiently to create a balance of pressures on the respective sides of the diaphragm 6, the pressures of the fluid in the upper and lower chambers being then 20 higher than before. So long as the total pressures against the respective sides of the diaphragm 6 are equal, the pressure on the delivery side of the static measuring device is always substantially that required to feed 25 the measured quantity of fluid to the spinning jet or jets or other point of use.

It should be noted that the upper cone of the double conical valve member 14 is normally positioned by the diaphragm 6 at a 30 relatively large distance from the throat 21 and this upper cone only functions to restrict the throat 21 when an abnormal or excess out-of-balance pressure develops in the upper chamber 10 (i. e. on the delivery side of the 35 static measuring device).

If an abnormal or excess out-of-balance pressure develops in the upper chamber 10 (due for instance to the spinning jet or jets or other point of use becoming badly choked) such that the resistance in the delivery from the pumping unit rises above the 40 pressure capacity of the pump, the diaphragm 6 causes the double conical valve member 14 to descend sufficiently for the upper cone of said valve member to close the throat 21, and thus entirely stop the supply 45 of fluid to the pump 2, the pumping unit ceasing to deliver the fluid to the spinning jet or jets until the cause of the out-of-balance condition is removed. Conversely, if an 50 abnormal or excess out-of-balance pressure develops in the lower chamber 11 (i. e. on the feed side of the static measuring device) the diaphragm 6 causes the double conical valve member 14 to rise sufficiently for the lower cone of said valve member to close the throat 21, and thus entirely stop the supply of fluid 55 to the pump 2, the pumping unit ceasing to deliver the fluid to the spinning jet or jets or other point of use until the cause of the 60 out-of-balance condition is removed.

In the form shown in this figure means are provided to ensure constant delivery from the pumping unit under variation of temperature when employing liquids (especially so-

lutions of cellulose acetate or other cellulose derivatives in volatile solvents) the viscosity of which decreases with an increase of temperature. As such means a small valve member 24 operated by the collapsible metal capsule 25 is provided to control the orifice 19 of the static measuring device. The valve member 24 is fixed to the metal capsule 25 which contains a quantity of paraffin oil, methylated spirit, ether or other suitable liquid, the capsule 25 being fixed to the threaded rod 26 passing through the plug 27 in the casing 5. By adjusting the nut 28 and the lock nut 29 the position of the valve member 24 may be adjusted or set relatively to the orifice 19. The valve member 24 is also fitted to or formed with a rod 30 which is fitted to a diaphragm 31, which diaphragm is exposed on one side to the pressure of the atmosphere and on the other side to the pressure of the fluid in the port 18, the diaphragm 31 thereby serving to obviate operation of the valve member 24 under changes of pressure in the spinning solution or other fluid. Should the temperature of the fluid in the pumping unit increase, the metal capsule 25 is expanded by the liquid contained therein and moves the valve member 24 to restrict the orifice 19 by the required amount; conversely, if the temperature of the fluid in the pumping unit decreases, the metal capsule 25 is contracted and increases the aperture between the valve member 24 and the orifice 19 by the required amount.

For starting up the unit when the aperture between the throat 21 is closed by the double conical valve member 14, for instance when starting up the pumping unit initially or after removal of the cause of either of the before mentioned excess or abnormal out-of-balance conditions, the screw valve member 32 is temporarily opened to allow fluid to pass from the inlet pipe 1 via the port 33 and port 22 to the pump 2. Fluid so passing to the pump 2, passes from the pump 2 via the port 16, through the lower chamber 11, static measuring device 4, port 18 and port 17 to the upper chamber 10, and by these means operates the diaphragm 6 to open the aperture between the double conical valve member 14 and the throat 21 to put the pumping unit in operation.

If the double conical valve member 14 is replaced by a needle valve member (which replacement may conveniently be considered as equivalent to omitting the upper cone of the double conical valve member 14) the said needle valve member will function to control the supply of fluid to the inlet side of the pump 2 precisely in the manner in which the lower cone of the double conical valve member 14 functions. The needle valve member however will not function to cut off the supply of fluid to the pump 2 when an abnormal or excess out-of-balance pressure develops on

the delivery side of the static measuring device, but it may be so positioned relatively to the throat 21 that it cuts off entirely the supply of fluid to the pump 2 when an excess out-of-balance pressure develops on the feed side of the static measuring device.

Referring to Figure 5. 1 is the supply pipe or header leading from the source of supply (not shown) for instance a gear wheel pump. 10 2, 2^a are the respective pumping units, these pumping units being constructed and arranged to operate precisely as described with reference to Figures 1, 2 and 3.

The spinning solution passes from the 15 source of supply (not shown) under any suitable and relatively low pressure, via the header or supply pipe 1, the branch pipes 4, 4^a, thence respectively through the pumping units 2, 2^a to the spinning jets 5, 5^a, these jets 20 extruding the solution into the cells 6 of the spinning metier or cabinet where the artificial silk filaments are formed by the evaporation of the volatile solvent in the known manner.

25 Should the supply of fluid from one or more of the branch pipes 4, 4^a to the pumps 3, 3^a of the pumping units be cut off due to development of excess out-of-balance pressure in either the upper or lower chamber of 30 the respective pressure balance valves of the pumping units, the delivery from the unit or units concerned will cease until the cause of the out-of-balance condition is removed.

35 What I claim and desire to secure by Letters Patent is:—

1. Pumping apparatus for delivering artificial silk spinning solutions or other fluids, comprising at least one pumping unit, itself 40 comprising a pump, an inlet port to said pump, a static measuring device and a pressure balance valve, whereof the delivery side of the pump communicates with the inlet side of the static measuring device, said pressure balance valve comprising (a) a motor member subjected on the one side to the pressure of the inlet side of the static measuring device and on the other side to the pressure of the delivery side of the static measuring device 45 and of the delivery from the pumping unit and (b) a valve member operatively connected to said motor member and arranged to control the inlet port to the pump, thereby controlling the supply of fluid to said pump, 50 and means for establishing a given pressure difference across the static measuring device and for compensating for the drop in pressure of the fluid in its passage through said device, thereby enabling a balance of pressures to be established on the respective sides of the motor member of the pressure balance valve.

55 2. Pumping apparatus for delivering artificial silk spinning solutions or other fluids, comprising at least one pumping unit, itself

comprising a pump, an inlet port to said pump, a static measuring device being an orifice of determined dimensions, and a pressure balance valve, whereof the delivery side of the pump communicates with the inlet side of the static measuring device, said pressure balance valve comprising (a) a motor member subjected on the one side to the pressure of the inlet side of the static measuring device and on the other side to the pressure of the delivery side of the static measuring device and of the delivery from the pumping unit and (b) a valve member operatively connected to said motor member and arranged to control the inlet port to the pump, thereby controlling the supply of fluid to said pump, and means for establishing a given pressure difference across the static measuring device and for compensating for the drop in pressure of the fluid in its passage through said device, thereby enabling a balance of pressures to be established on the respective sides of the motor member of the pressure balance valve.

3. Pumping apparatus for delivering artificial silk spinning solutions or other fluids, comprising at least one pumping unit, itself comprising a pump, an inlet port to said pump, a static measuring device and a pressure balance valve, whereof the delivery side of the pump communicates with the inlet side of the static measuring device through one side of the pressure balance valve, said pressure balance valve comprising (a) a motor member subjected on the one side to the pressure of the inlet side of the static measuring device and on the other side to the pressure of the delivery side of the static measuring device and of the delivery from the pumping unit and (b) a valve member operatively connected to said motor member and arranged to control the inlet port to the pump, thereby controlling the supply of fluid to said pump, and means for establishing a given pressure difference across the static measuring device and for compensating for the drop in pressure of the fluid in its passage through said device, thereby enabling a balance of pressures to be established on the respective sides of the motor member of the pressure balance valve.

4. Pumping apparatus for delivering artificial silk spinning solutions or other fluids, comprising at least one pumping unit, itself comprising a pump, an inlet port to said pump, a static measuring device being an orifice of determined dimensions and a pressure balance valve, whereof the delivery side of the pump communicates with the inlet side of the static measuring device through one side of the pressure balance valve, said pressure balance valve comprising (a) a motor member subjected on the one side to the pressure of the inlet side of the static measuring device and on the other side to the pressure of the inlet side of the static measuring device and of the delivery from the pumping unit and (b) a valve member operatively connected to said motor member and arranged to control the inlet port to the pump, thereby controlling the supply of fluid to said pump, and means for establishing a given pressure difference across the static measuring device and for compensating for the drop in pressure of the fluid in its passage through said device, thereby enabling a balance of pressures to be established on the respective sides of the motor member of the pressure balance valve.

side to the pressure of the delivery side of the static measuring device and of the delivery from the pumping unit and (b) a valve member operatively connected to said motor member and arranged to control the inlet port to the pump, thereby controlling the supply of fluid to said pump, and means for establishing a given pressure difference across the static measuring device and for compensating for the drop in pressure of the fluid in its passage through said device, thereby enabling a balance of pressures to be established on the respective sides of the motor member of the pressure balance valve.

5. Pumping apparatus for delivering artificial silk spinning solutions or other fluids, comprising at least one pumping unit, itself comprising a pump, an inlet port to said pump, a static measuring device and a pressure balance valve, whereof the delivery side of the pump communicates with the inlet side of the static measuring device through one side of the pressure balance valve, said pressure balance valve comprising (a) a motor member subjected on the one side to the pressure of the inlet side of the static measuring device and on the other side to the pressure of the delivery side of the static measuring device and of the delivery from the pumping unit and (b) a valve member operatively connected to said motor member and arranged to control the inlet port to the pump, thereby controlling the supply of fluid to said pump, and to close the inlet port to the pump when an excess out of balance pressure develops on the delivery side of the static measuring device, and means for establishing a given pressure difference across the static measuring device and for compensating for the drop in pressure of the fluid in its passage through said device, thereby enabling a balance of pressures to be established on the respective sides of the motor member of the pressure balance valve.

6. Pumping apparatus for delivering artificial silk spinning solutions or other fluids, comprising at least one pumping unit, itself comprising a pump, an inlet port to said pump, a static measuring device being an orifice of determined dimensions and a pressure balance valve, whereof the delivery side of the pump communicates with the inlet side of the static measuring device through one side of the pressure balance valve said pressure balance valve comprising (a) a motor member subjected on the one side to the pressure of the inlet side of the static measuring device and on the other side to the pressure of the delivery side of the static measuring device and of the delivery from the pumping unit and (b) a valve member operatively connected to said motor member and arranged to control the inlet port to the pump, thereby controlling the supply of fluid to said pump and to close the inlet port to the pump both when an excess out of balance pressure develops on the de-

said pump, and to close the inlet port to the pump both when an excess out of balance pressure develops on the delivery side of the static measuring device and when an excess out of balance pressure develops on the inlet side of the static measuring device, and means for establishing a given pressure difference across the static measuring device and for compensating for the drop in pressure of the fluid in its passage through said device, thereby enabling a balance of pressures to be established on the respective sides of the motor member of the pressure balance valve.

7. Pumping apparatus according to claim 3 and comprising as the means for establishing a given pressure difference across the static measuring device and for compensating for the drop in pressure of the fluid in its passage through said device, a spring acting upon the motor member of the pressure balance valve.

8. Pumping apparatus according to claim 3 and wherein said pumping unit further comprises a compensating device adapted to operate under variations of temperature to control the aperture of the static measuring device and thereby secure constant flow through said device under variations of temperature.

9. Pumping apparatus according to claim 3 and wherein said pumping unit further comprises a compensating device adapted to operate under variations of temperature to control the aperture of the static measuring device and thereby secure constant flow through said device under variations of temperature, said compensating device comprising a valve member controlling the aperture of the static measuring device and a bi-metal strip secured on the one end and carrying said valve member on the other end.

10. Pumping apparatus for delivering artificial silk spinning solutions or other fluids, comprising at least one pumping unit, itself comprising a pump, an inlet port to said pump, a static measuring device being an orifice of determined dimensions and a pressure balance valve, whereof the delivery side of the pump communicates with the inlet side of the static measuring device through one side of the pressure balance valve, said pressure balance valve comprising (a) a piston motor member subjected on the one side to the pressure of the inlet side of the static measuring device and on the other side to the pressure of the delivery side of the static measuring device and of the delivery from the pumping unit and (b) a slide valve member operatively connected to said piston motor member and arranged to control the inlet port to the pump, thereby controlling the supply of fluid to said pump and to close the inlet port to the pump both when an excess out of balance pressure develops on the de-

- livery side of the static measuring device and when an excess out of balance pressure develops on the inlet side of the static measuring device, a spring acting upon the piston motor member of the pressure balance valve by pressing against said motor member on the side thereof subjected to the pressure of the delivery side of the static measuring device, said spring serving to establish a given pressure difference across the static measuring device and to compensate for the drop in pressure of the fluid in its passage through said device, thereby enabling a balance of pressures to be established on the respective sides of the piston motor member of the pressure balance valve.
11. Pumping apparatus according to claim 10 and wherein said pumping unit further comprises a compensating device adapted to operate under variations of temperature to control the aperture of the static measuring device and thereby secure constant flow through said device under variations of temperature.
12. Pumping apparatus according to claim 10 and wherein said pumping unit further comprises a compensating device adapted to operate under variations of temperature to control the aperture of the static measuring device and thereby secure constant flow thru said device under variations of temperature, said compensating device comprising a valve member controlling the aperture of the static measuring device and a bi-metal strip secured 35 on the one end and carrying said valve member on the other end.
13. Pumping apparatus for delivering artificial silk spinning solutions or other fluids, comprising at least one pumping unit, it- 40 self comprising a pump, an inlet port to said pump, a static measuring device being an orifice of determined dimensions and a pressure balance valve, whereof the delivery side of the pump communicates with the inlet side 45 of the static measuring device through one side of the pressure balance valve, and wherein said pumping unit comprises a gear wheel pump, a casing bored to two different inter- 50 communicating diameters, a moving member comprising a piston motor member operating in the larger bore of the casing and a hollow slide valve member operating in the smaller bore in the casing, holes in said moving member communicating between the interior of 55 the slide valve member and the bores of the casing for enabling the moving member to operate in said bores, a passage-way in said casing and a disc formed with an orifice of determined dimensions mounted in said pas- 60 sage-way, said orifice constituting the static measuring device, an inlet port communicat- 65 ing between the larger bore and said passage-way on the one side of said disc and a delivery port communicating between the larger bore 66 and said passage-way on the other side of

said disc, the piston motor member being arranged to operate intermediately between said inlet port and said delivery port, a port in said casing communicating with the delivery side of the gear wheel pump and the larger bore at a point in communication with said inlet port, a port communicating with said delivery port and the delivery from the pumping unit, an inlet port to the gear wheel pump and an annular groove in the smaller bore communicating with said port, a supply port and an annular groove in the smaller bore communicating with said supply port, an inclined annular groove around the slide valve member, the slide valve member being 70 adapted to control the inlet port to the gear wheel pump and the supply of fluid to said pump by the positioning of said inclined annular groove relatively to said annular grooves in the smaller bore, and adapted to close the inlet port to the gear wheel pump by moving the inclined annular groove out of register with the said annular grooves in the smaller bore both when an excess out of balance pressure develops on the delivery side 75 of the static measuring device and when an excess out of balance pressure develops on the inlet side of the static measuring device, a spring arranged to press against the said piston motor member on the side thereof exposed to the pressure of the delivery port, i. e. the side subjected to the pressure of the delivery side of the static measuring device, said spring serving to establish a given pressure difference across the static measuring device and to compensate for the drop in pressure of the fluid in its passage through 80 said device, thereby enabling a balance of pressures to be established on the respective sides of the said piston motor member.

14. Pumping apparatus according to claim 13 and wherein said pumping unit further comprises a compensating device itself comprising a valve member arranged to control the aperture of the orifice in the disc, i. e. the aperture of the static measuring device, and a bi-metal strip secured to the casing on the one end and carrying said valve member on the other end, said compensating device being adapted to operate under variations of 85 temperature to control the aperture of the static measuring device and thereby secure constant flow through said device under variations of temperature.

In testimony whereof I have hereunto 90 subscribed my name.

EDWARD KINSELLA.
